COMPUTING AND ACCOUNTING MACHINE

John Mueller, North Bergen, N. J., assignor to
 Remington Rand Inc., Buffalo, N. Y., a corporation of Delaware

Application July 24, 1941, Serial No. 403,784

8 Claims. (Cl. 235—133)

The invention relates to computing and accounting machines, and more especially to the totalizer mechanism of such machines.

Totalizers of accounting machines have been made so that they could be "split"; that is to say, so that the tens transfer mechanism could be disabled at one or more points when desired, and the totalizer could then be used for adding in a plurality of columns. It has also been proposed to construct a totalizer settable at will into a condition such that, when the totalizer was moved into engagement with its actuators, a certain group of its wheels would be held back out of engagement, but without disabling the transfer. The wheels thus restrained were not affected by the differential movements of the actuators, but were available to register amounts transferred to them from wheels of lower order. Machines equipped with such totalizers as above referred to can be set up by the operator so as to adapt them for different uses. It is an object of the present invention to improve not only the means for splitting a wide totalizer, but also the means for disabling portions of it altogether, leaving the actuators for the disabled wheels available for other uses. This is especially useful in instances where said actuators are also associated with, or themselves constitute, type carriers, and particularly where said type carriers bear alphabetic or other types in addition to numerals. Thus, actuators associated with the totalizer or with some part thereof, may be used at one time for adding and at another time actuators associated with disabled totalizer wheels may be used for printing text including alphabetic text or other designatory matter while still using a portion of the totalizer for computing. To provide for this flexibility of use is one of the objects of the invention.

Another object of the invention is to render the totalizer more certain to operate correctly in a respect which will be pointed out.

To the above and other ends which will be apparent from the following specification, the invention consists of certain features of construction and combinations and arrangements of parts, all of which will be fully described herein and particularly pointed out in the claims.

In the accompanying drawings, in which one specific instance of the invention and one application of it are illustrated in detail,

Fig. 1 is a general front to rear vertical section of a Powers tabulating machine to which the invention is applied;

Fig. 2 is a partial right hand elevation showing some of the mechanism just inside the right hand

frame member of the head section of the machine, said member having been sectioned away;

Fig. 3 is a similar view but showing some of the mechanism just outside the left hand frame member, the web of the latter sectioned away, the flange only of it showing;

Fig. 4 is a view on a small scale showing some linkage in and associated with a totalizer detached from other mechanism. The parts are in the positions they occupy in the first half of a total taking cycle;

Fig. 5 is a partial front to rear vertical section through the middle of the head and showing two totalizers and some cooperating parts;

Fig. 6 is a longitudinal section through one of the totalizers and some cooperating parts and drawn on a slightly larger scale than Fig. 5;

Fig. 7 is a fragmentary cross section on the line 7—7 of Fig. 6 and looking in the direction of the arrows;

Fig. 8 is a top plan view of a totalizer and some associated mechanism on a slightly larger scale than Fig. 6 and with parts broken away;

Fig. 9 is an enlarged fragmentary isometric view showing three totalizer wheel supports, one of them being disabled;

Fig. 10 is a fragmentary front elevation of a portion of the totalizer in section on the line 10—10 of Fig. 6;

Fig. 11 is a fragmentary view showing one of the type carriers.

In the specific instance illustrated in the drawings, the invention is shown embodied in a punched card tabulating machine of the sort described and claimed in the application for Letters Patent for Tabulating and accounting machines, filed November 13, 1937, by W. W. Lasker, Jr., executor of the will of W. W. Lasker, deceased, and J. Mueller, S. N. 174,354; in the corresponding British patent of Remington Rand Inc., for Statistical machine, No. 522,562, accepted June 20, 1940; and in the application for patent for Tabulating and accounting machine, filed February 1, 1940, by J. Mueller, S. N. 316,739. Except as hereinafter explained, the machine fragmentarily illustrated and described herein, may be as described in said patent and applications.

As shown generally in Fig. 1, the machine comprises a base section 30, and mounted on it a head section 31. The base section is constructed substantially as described in the patent to W. W. Lasker, No. 2,044,119, dated June 16, 1936, and is the same as has been in use in Powers tabulators for a number of years. Punched cards are fed from a hopper 32, by picker 33 and feed rolls 34,

into a sensing chamber in the base of an upper pin box 35, from which they pass into a receptacle 36. The sensing pins 37 are in a lower pin box 38 which is reciprocated by eccentrics 40 on the motor driven main base shaft 41. They elevate set pins 42 in the upper pin box 35, and through them operate Bowden wires 43 in a translator 44.

In the head section 31, the Bowden wires 43 displace code or "permutation" bars 45 which, in turn, control stops 46 for arresting the combined type carriers and totalizer actuators 47. The latter are guided on rods 48, are moved upward against the stops 46 by springs (not shown), and are moved down to normal position by a restoring bar 50. As far as the present invention is concerned, the actuators 47 may be reciprocated and controlled by any suitable means. The head section has a rear drive shaft 51 and a front drive shaft 52, geared to rotate at the same speed as the main base shaft 41. The restoring bar 50 is reciprocated by cranks, one on each end of the shaft 51, which cranks drive pitmans 53 (Fig. 3) with a motion modified by certain guide discs in a manner not necessary here to be explained.

In the machine of the prior disclosures, there is a long continuous series of the actuators 47, each of which carries a series of types 59, including both numeric and alphabetic types (Fig. 11). A number of totalizers may be placed in front of said actuators in two tiers, mounted on two dove-tail shaped frame bars 54 and 55; and the construction is such that a totalizer may be mounted in any desired position on either of said bars so as to be actuated by any desired succession of the actuators. In the assembly of each individual machine, totalizers are so mounted in number and location appropriate to the use to which the particular machine is to be put. The totalizer illustrated in the drawings is adapted to this situation, though the invention, as to most of its features, is applicable to other machines. The specific totalizer illustrated will be described in detail.

The totalizer may be of a width greater than is likely to be needed for a single number, and it is so constructed that it can be split at a desired point or points, so as to divide it in effect into a plurality of totalizers, each comprising whatever number of register wheels is required by the work. As shown, and preferably the totalizer can be split, by the operator of the machine, at any point in its width he desires. The drawings were made from a totalizer of a width of forty denominations. The totalizer wheels 56 (Fig. 6) are each journaled on a bearing 57 riveted to the left hand face of a sheet metal lever 60 which, with certain differences to be described, resembles levers contained in the totalizers of the prior disclosures. In Fig. 6 the section is taken on the left face of one of these levers, and the wheel 56 and cooperating parts shown in full lines, are on the lever 60 thus sectioned away. The levers 60 are guided and pivoted in a comb bar 61 having a groove cut in its upper edge in which lie studs 62, one projecting leftward from each of the levers and constituting its pivot. The rear parts of the levers are guided in upper and lower comb bars 63 and 64, and they rest on a flanged cross bar 65. When the wheels 56 are in mesh with the racks 47, the levers 60 are individually spring urged to swing upward at their rear ends. Each lever is normally held down by a transfer dog 66 engaging a shoulder of the lever. The dog 66 is urged into engagement by a spring 67, and is connected by

a link 68 with a bell-crank transfer pawl 70, pivoted at 71 to the left hand face of the next lever 60 to the right, (Fig. 8) and cooperating in a usual way with a transfer tooth 72 on the wheel 56 on that lever. When said wheel turns from 9 to 0, said tooth rocks the pawl 70 counterclockwise, withdrawing the dog 66 and permitting the left hand lever 60 to rise at its rear end. The wheel 56 on said left hand lever is thus moved individually along its actuator 47 (lengthwise of said actuator) a distance to turn said wheel one tooth, when said lever is arrested by a shoulder 73 thereof striking the comb bar 63. Each wheel 56 is held, when out of mesh, by a detent lever 74 pivoted to the lever 60 at 75, and urged against the teeth of the wheel by a spring 76. As thus far described, the register wheels, their levers 60 and the transfer and detent devices, are all substantially the same as the upper set of such devices in the totalizer of the prior disclosures. The transfer dogs 66 are pivoted on a rod 77 seated in a comb bar 78.

The comb bar 61 is a part of a frame which swings rearward and back to move the wheels 56 into and out of mesh with the racks. Said frame may be variously constructed. As shown, its principal member consists of a round rod 80 (Figs. 6, 9 and 10) having a longitudinal cutout with one radial wall against which a flange of the bar 61 is secured by screws 81. At its ends it has eccentric trunnions 82 journaled in bearings in the stationary base casting 83 of the totalizer unit, said bearings including journal caps 79. The flange on the bar 61 extends only the length of the thick portion of the member 80, the ends of said bar projecting a little beyond the base member 83. The member 83 is detachably and adjustably secured to the dove-tail shaped bar 54 or 55 in about the same manner as in the prior disclosures, viz., by a dove-tail undercut fitting the rear edge of the bar and clips 79 screwed tight against the forward edge of the bar.

The frame of the totalizer proper comprises right and left hand frame plates 84 (Figs. 5, 8 and 10) which plates are rigidly connected by the cross bars 63, 65, and 78. The bar 65 is supported at its ends by brackets 85 secured to the plates 84, and the comb 64 is supported from the bar 65 through a bar 86. Said bar 86 and the comb 78 are made fairly heavy for stiffness on account of the width of the totalizer. Near their front ends the frame plates 84 occupy the extreme right and left end slots of the comb bar 61 (Figs. 5 and 10). Each has a stud 87 pivoted in the groove of said bar and retained in place by a clip 88 secured by a screw to the end of the bar 61. The rear ends of the frame plates 84 are supported by links 90 pivoted thereto and to the base casting 83. The whole construction is such that when the member 80 is rocked clockwise as viewed in the drawings, the totalizer, including the levers 60 and the framework in which they are guided, moves as a whole rearward until the wheels are properly meshed with the racks. The motion is limited by stop plates 92, one screwed to each side of the base 83, arresting lugs 93 depending from the frame plates 84. The totalizer is moved to its forward position by springs 94 (Fig. 5).

The rocker comprising the bar 61 and shaft 80 also includes at each end a plate-like lever 95 which (Figs. 9 and 10) is secured by a screw 96 against the end of the trunnion 82 and which 75 has a fork embracing the end of the bar 61, so

that the lever and said bar are keyed together to rock in unison. Each lever 95 has a forwardly directed arm which is connected by an upright link 97 to a lever 98, pivoted on a transverse shaft 99 supported by the frame plates 84. The rear arms of the levers 98 are connected into a bail by a rod 100 which overlies the forward ends of the detent levers 74. When the rocker is rocked clockwise to engage the totalizer wheels with the racks, the rod 100 depresses the forward arms of said detents and lifts them out of the wheels. A similar construction was described in the prior disclosures.

As in the Mueller application, S. N. 316,739, two levers 101 pivoted to the outer faces of the frame plates 84, are connected by a bail bar 102 overlying the levers 60, each lever 101 being urged clockwise by a spring 103 and having an arm underlying the bail bar 100. When the totalizer is shifted rearward to mesh the wheels, and the bar 100 descends, the bar 102 is raised away from the levers 60, leaving them free to swing upward in case of transfer. When the wheels move out of mesh and the bar 100 rises, the springs 103 depress the bar 102, to assure that any elevated lever 60 is returned to normal.

Spring pressure is applied to the totalizer levers 60 to move their rear ends upward to transfer the tens, in the same manner as in the prior disclosures. Each of said levers forward of its pivot 62 has pivoted thereto at 104 a bell-crank 105 which is urged clockwise (Fig. 6) by a spring 106 connected to an arm of the bell-crank and to the end of the lever 60, the motion being limited by a lug 107 formed off from said lever. A roller 108 at the forward end of the bell-crank, underlies a channel bar 110 secured to a cross bar 111. There are two of these cross bars, one for the upper and the other for the lower tier of totalizers, and they are connected together at their ends into a rigid rectangle by vertical bars 112 (Fig. 2). Each of the bars 112 is pivotally mounted on two parallel rock arms or levers 113, pivoted at 114 to the right and left hand main frame pieces 115, respectively, of the head section of the machine. The lower lever 113 of each pair carries a follower roller 116 bearing against a cam 117 on the front drive shaft 52, against which cams the parts are held by springs 118. The cams are so designed as to depress the bars 111 just after the totalizer wheels have been engaged with the racks and to allow them to rise, deenergizing the springs 106 in time to permit any operated levers 60 to drop down to normal position when the wheels are out of mesh with the racks.

In the prior disclosures the bell-cranks 105 were on the upper ones of two sets of levers like the levers 60, so that the rollers 108 bore against the under surface of the bars 111 themselves. The present levers 60 occupy vertically about the position of the former lower set, and the members 110 are inserted to take up the space thus created between the followers 108 and the bars 111. It is contemplated that it may in some instances be desired to employ both the present adding and subtracting totalizers and also the former adding and subtracting totalizers side by side in the same machine. It is, therefore, preferable that the member 110 be only long enough to cover the followers 108 of the present totalizer (to the number of forty in the specific instance described) leaving the bars 111 otherwise in condition for use with the former totalizers.

The totalizers are moved into and out of en-

gagement with their actuators by the rocking of two shafts, viz., a shaft 120 for the upper tier and a shaft 121 for the lower tier of totalizers, these shafts and the means for operating them and for controlling their operation being identical with those of the prior disclosures. One of the levers 95 (Fig. 5) (the right hand one, as illustrated) has a link 122 pivoted thereto at 123, said link being pivoted at 124 to a lever 125 fast on a stub shaft 126 journaled in a boss at the base casting 83. The lever 125 is operated by a link consisting of a rear section 127 and a front section 128, said sections slidably connected together by slots and headed pins 130 and by stiff springs 131 tending to maintain the compound link at its maximum length. In case a totalizer wheel tooth collides with a tooth of the actuator, the link can yield, stretching the springs 131 instead of injuring the mechanism. An arm 132 fast on the rock shaft 120 or 121 has a stud 133 playing in a closed slot 134 in the forward part of the link. When the shaft 120 is rocked clockwise, or the shaft 121 counter-clockwise, the stud 133 acting on the link 128, 127 rocks the lever 125 which, through link 122, rocks the rocker 95, 80, 61 clockwise, moving the totalizer rearward until arrested by the stops 92 thus bringing the wheels into mesh with the racks (Fig. 4). The parts are so designed that in this movement the radius 126, 124 of the lever 125, and the axis 124, 123 of the link 122, have the action of a toggle, acting on the lever 95 with an increasing leverage and a decelerated velocity, so that the totalizer is brought to its engaged position with a sufficiently powerful pressure and is brought to rest gently without too much jar. In its final position the toggle lacks enough of being dead centered to assure that the springs 94 can restore the parts when the arms 132 return to their forward positions.

In order to provide for disabling the totalizer in its entirety when desired, the slot 134 is made of such length that the stud 133 can move idly in it without operating the link, and the surplus length is covered by a displaceable interponent. As here shown said interponent consists of a sheet metal piece 135, pivoted at 136 to the link section 128 and, when in active position, having its front end covering a portion of the slot 134 and lying in the path of the head of the stud 133 and communicating the motion of said stud to the link, as shown in Fig. 4 and in the lower totalizer in Fig. 5. The interponent 135 can, however, be swung by hand to the position shown in the upper totalizer of Fig. 5, where it is out of the path of said stud. In the setting illustrated in Fig. 5 when the shafts 120 and 121 are rocked, the lower totalizer will be brought into engagement and not the upper. The interponent is influenced by a spring 137 so disposed that it tends to retain said interponent in either of its positions, which positions are defined by two arms 138 of said interponent being arrested by the pin 139 to which the spring is connected.

In operating the adding and subtracting totalizer of the prior disclosures, arms similar to the arms 132 had the double duty of first reversing the totalizer from one sign to the other, on occasion, and then moving the totalizer into engagement, so that said arms have a longer stroke than is required for the present totalizer, which accounts for the lost motion between the stud 133 and the interponent 135 indicated in Fig. 5. In another machine such lost motion would, of course, not be necessary.

In order to provide for splitting the totalizer at any desired point or points and for disabling any desired denominational elements of it, means are provided whereby a lever 60 may be set bodily forward of its normal position relative to other such levers, and secured there, thus displacing the wheel 56 on said lever away from its actuator 47. In the instance illustrated, each lever 60 is provided with two studs 62 (Figs. 6 and 9) one behind the other, the forward stud resting in the notch in the bar 61 when the element is in use. The forward end of the lever may be lifted by hand and the lever be drawn toward the front of the machine and the rear stud seated in the notch as shown in the middle one of the three levers in Fig. 9. This locates that totalizer wheel 56 so far forward that it does not engage its rack 47 when the bar 61 is swung rearward, thus leaving that rack and type carrying bar entirely free for other use such as to print either alphabetic characters or numbers not to be added.

In order to prevent accidental displacement of the studs 62 from the bar 61, a locking flap or bail 140 (Fig. 6) is provided, having at its ends ears pivoted on the cross rod 99 and urged by a spring 141 counter-clockwise to its locking position where it is arrested by ears 142 (Fig. 8) striking the front edges of the frame plates 84. The lower edge of this bail stands just above the upper edges of the levers 60. When it is desired to change the setting of one of these levers, the bail 140 is swung by hand clockwise out of the way.

When a lever 60 is set forward in its disabled position, it rocks clockwise the transfer dog 66 which engages it. The link 68 for this dog is connected with the transfer pawl 70 of the next lower order, and which may still be in active condition. In order to permit of this swinging of the dog 66 without disturbing its pawl 70, said dog is connected with its link 68 by pin and slot, the pin moving to the forward end of the slot when the dog is swung as described.

In order to prevent swinging movement of a lever 60 which has been disabled as above described, each such lever has a finger 143 made at its under rear portion, and projecting forward in such position that, when the lever is set inactive said finger comes under the flange on the frame bar 65, as shown in Fig. 9, and locks the rear end of the lever down.

The setting of a lever 60 to its forward position to produce a split between two sections of the totalizer, acting through link 68, unlatches the dog 66 for the next lever 60 to the left. The pawl 70 then rests on a stud 69 on lever 60, to prevent said pawl from dropping down. Said lever 60 then becomes the units lever of the left hand section, and it will not be required to rise for transferring. In order to lock this units lever down, the following means are provided (Figs. 6, 7, 8, and 9). Near its rear end, each lever 60 has an ear 144 projecting from its right hand face, and an ear 145 from its left hand face, said ears so disposed that when one of the levers is set to its forward inactive position, its ear 145 lies on top of the ear 144 of the next lever 60 to the left. As the inactive lever is locked down at 143, its ear 145 locks down the units lever at its left. This is illustrated in Fig. 9 and also in Fig. 7 where the third lever from the left has been drawn forward, bringing its ear 145 into the plane on which the section is taken.

Within the range of the, say forty places, of the totalizer, adding columns of any desired width

may be located at any desired positions, and all other positions of the totalizer may be disabled entirely, the wheels never engaging the actuators. The bars 67 coordinated with these wheels may, therefore, be utilized for printing any desired numbers or text or for adding on another totalizer on the other bar 54 or 55. If the unused wheels were permitted to engage the actuators, such printing would cause a hodge-podge of numbers to be rolled into them, resulting in the printing of meaningless totals. Also, the spacing of the types on the type bar is only half that of the rack teeth, and alphabet types are interspersed between the numeral types, as shown in Fig. 11. When, for example, a bar 67 is set to print an "E," a tooth of the rack stands directly behind a tooth of the totalizer wheel 56, and if it were sought to move said wheel into engagement, the teeth would collide. This is obviated by setting the wheel back as described, so that it never engages the rack. Any desired denominations of the totalizer may be temporarily put out of use in the manner described.

A further improvement in the totalizer resides in the provision of a lock to assure that the levers 60 do not rise in total taking operations. In total taking, the wheels 56 are in engagement with the racks 47 on the up-strokes of the latter, and each said wheel and rack is arrested by the transfer lever 70 being struck on its abrupt edge by the transfer tooth 72 on the wheel. It has been found in practice that in rapid operation, the vibration set up by this blow may occasionally jar the dog 66 loose from the shoulder on the lever 60, allowing the latter to rise, thus causing the type carrying rack to move upward too far. In order to make this misoperation impossible even at high speed, a bail bar 146 (Figs. 4, 5, 6, and 8) normally stands as shown in Fig. 6 with its lower edge just back of the upper edges of all of the levers 60; but in total cycles this bar is swung forward so as to stand above said levers and positively to prevent them from rising as shown in Fig. 4. Said bar 146 may have at its ends arms 147 formed off therefrom and pivoted at 148 to ears formed off from a frame plate 150. The latter is here shown fastened to the frame and comb bar 63, which, in this wide totalizer, it serves to stiffen and strengthen.

The means for controlling the locking bar 146 would vary in detail in different machines. In the present instance, the left-hand arm 147 is prolonged downward and is connected by a link 151 with a bell-crank 152, conveniently pivoted on the cross shaft 99. Fig. 5 shows a pair of totalizers one above the other, and the bell-cranks 152 of the two totalizers are connected to rock in unison by a vertical link 153. The machine includes certain parts that are set in distinctive positions for total taking, and one of them, viz., the so-called "credit balance shaft" 154 is utilized in the present instance to operate the locking bail bars 146. As explained in detail in the prior disclosures, this shaft is rocked clockwise in Fig. 5 early in the blank stroke preceding a total stroke, and is held so rocked throughout the blank stroke and until the latter part of the total or grand total cycle, when it rocks back to its normal position. An arm 155 is mounted fast on this shaft and is connected by a link 156 with the lower bell-crank 152 so as to rock the latter counter-clockwise when shaft 154 is rocked as shown in Fig. 4. This operates the lower locking bail 146 through its link 151, and, through the link 153, upper bell-crank 152 and link 151, it

operates the upper locking bar 146, maintaining all of the levers 60 locked down during the total taking operation.

As shown in Fig. 6, the link 156 is connected with the lower bell-crank 152 by pin and slot 157 so as to allow the movement of the lower totalizer into and out of engagement with the racks without rocking the bell-crank. At its forward end said link 156 is connected with the arm 155 by pin and slot and spring 158, the spring tending to hold the pin in the rear end of the slot. The motion of the arm 155 is at least sufficient, when taking a total from the upper totalizer, to take up the lost motion at 157 and to operate the locks 146. When taking a total from the lower totalizer, as shown in Fig. 4, there is an excess of motion of the arm 155, which stretches the spring 158.

The mechanism of the invention may be modified in detail and it can be applied or adapted to various machines without departing from the invention. The cooperating mechanism of the particular machine which is fragmentarily illustrated in the drawings is fully described in the prior disclosures, but it may be worth while to describe some of it briefly herein.

Fig. 2 is a sectional elevation taken just inside the right hand frame member 115, and showing some of the mechanism at the right hand part of the machine. The total taking control unit 160 contains two cam shafts, one set into rotation to take a total (two cycles) and the other to take a grand total (three cycles). The cams rock counter-clockwise several levers 161, pivoted on a post 162. Among these is one which, through one of several links 163, operates bell-crank 164, link 165, lever 166, link 167, and arm 168 fast on the "credit balance" shaft 154, which, as above described, it was found convenient to utilize to throw in the locking balls 146 (Fig. 6). This shaft is "pulled" at the beginning of each total taking operation (early in the blank cycle preceding a total cycle) and is held pulled until near the end of the total taking operation.

The so-called "total shaft" 170, Fig. 2, is "pulled" (rocked counter-clockwise) just before a total cycle by another of the levers 161 acting through one of the links 163, a lever 171, link 172, one of a plurality of bell-cranks 173, link 174, and arm 175, the latter fast on shaft 170. This shaft performs several functions, one of which will be described briefly.

The "grand total shaft" 176 is similarly "pulled" with similar results, just before a grand total cycle, by a lever 161, link 163, lever 171, link 178, a bell-crank 173, a short link hidden by link 174, and an arm 180 fast on the shaft.

The mechanism for rocking the shafts 120 and 121 to move the totalizers into and out of engagement, is partially shown in Fig. 3, which is a view from the right of parts on the outer side of the left hand frame member 115, the web of said member being sectioned away. Fast on the lower shaft 121 is a lever or arm 181 urged by a spring 182 clockwise against a fixed post 183. The arm 181 is made of two plates connected together by a pin 184 on which, between the plates, four devices are pivoted. Reference number 185 designates a bifurcated link or coupler, the fork of which embraces a pin 186 on the upper end of a follower lever 187 pivoted loosely on a fixed post 188 and drawn clockwise by a spring 189, against a total taking cam 191 on the front drive shaft 52. The forked coupler 185 is urged counter-clockwise by a spring 192, which presses

the lower tine of the fork against the underside of the pin 186 and holds the upper tine away from said pin. Said upper tine has a ratchet-shaped tooth which is normally out of engagement with the pin 186, but can be moved into engagement by depressing the coupler. The cam 191 swings the lever 187 rightward at the mid-part and leftward at the latter part of each cycle. The total shaft 170 is pulled in the latter part of the blank cycle and, through link 189, pin, slot, and spring connection 193 and bell-crank 194, depresses coupler 185, by means of a roller 195 on said bell-crank. Lever 187, when swung leftward will then act to rock the shaft 121 counter-clockwise, moving the lower totalizers into engagement to take a total as hereinbefore described.

Addition on the lower totalizers is controlled by a second lever like lever 187 and just behind it in Fig. 3. The add cam which operates this lever gives the timing appropriate to addition. Pivoted on pin 184 is a second coupler similar to the coupler 185, but its tooth for cooperation with the pin like 186, is on the lower tine of the fork and is, therefore, normally in engagement. The total shaft depresses it out of engagement by a bell-crank like 194.

The upper shaft 120 has fast thereon an arm 196 rocked counter-clockwise by a spring 197 against the post 183. This arm has pivoted there-to two couplers similar to those on arm 181, and operated, respectively, by two follower levers 200, both pivoted on the post 188 and drawn by springs 201 leftward in Fig. 3 to press their follower rollers 202 against the rear faces of add and total cams, respectively, on the shaft 52. The levers 200 are positively rocked clockwise by their cams, and the couplers like 185 differ from the latter in acting as pull links instead of push links. Two bell-cranks 194 (there are four of these in all) are connected by links to arms fast on the grand total shaft 176. The add coupler is normally active, but is depressed out of engagement and the grand total coupler is depressed into engagement by the rocking of the grand total shaft 176.

While I have described what I consider to be a highly desirable embodiment of my invention, it is obvious that many changes in form could be made without departing from the invention, and I, therefore, do not limit myself to the exact form herein shown and described, nor to anything less than the whole of my invention as hereinbefore set forth, and as hereinafter claimed.

What I claim as new and desire to secure by Letters Patent is:

1. In a totalizer in which the transfer of the tens is effected by moving a totalizer wheel along its actuator relatively to other wheels, a totalizer wheel support settable relative to other wheel supports away from the actuator, so as to disable the wheel on said support by preventing it from engaging its actuator, and means for concomitantly locking the support so set against transfer movement.
2. In a totalizer in which the transfer of the tens is effected by moving a totalizer wheel along its actuator relatively to other wheels, a totalizer wheel support settable relative to other wheel supports away from the actuator, so as to disable the wheel on said support by preventing it from engaging its actuator, means for concomitantly locking the support so set against transfer movement, and means also acting concomitantly to lock against transfer movement the wheel support of next higher order.

3. In a totalizer in which the transfer of the tens is effected by moving a totalizer wheel along its actuator relatively to other wheels, a totalizer wheel support settable relatively to other wheel supports away from the actuator, so as to disable the wheel on said support by preventing it from engaging its actuator, and means acting concomitantly to lock against transfer movement the wheel support of next higher order.

4. In a totalizer, a series of totalizer wheels, individual supports for said wheels each pivotally movable to sweep its wheel along the associate actuator to transfer the tens, means for sustaining said supports for said pivotal movement, and means whereby each of said supports and wheels is individually settable at the point of pivotal support away from its actuator, disabling any wheel so set and making its actuator free to be operated without turning said wheel while leaving other wheels operable both to the right and to the left of the wheel or wheels so set.

5. In a totalizer of the kind in which the totalizer wheels are mounted on individual supports each actuated to move its wheel along its associate wheel actuator to transfer the tens, a wheel support in the form of a lever having two pivots at different distances from the actuator and settable to either pivot at will, the wheel on said lever being engageable with its actuator in one setting and not in the other.

6. Totalizer wheels each mounted on a lever which swings the wheel along the rack to transfer, each said lever being individually settable in

the totalizer frame in a direction away from the actuator so as to keep that particular wheel out of mesh when other wheels engage their actuators, a tooth on said lever moved by such displacement into engagement with a tooth on the frame to lock the lever against transfer movement, and a tooth on the lever moved by such displacement over a tooth on the lever of next higher order to lock said higher order lever against transfer movement.

7. In a totalizer in which the totalizer wheels are moved along their actuators to transfer the tens, a wheel-carrying lever settable in the totalizer frame away from the associate actuator relatively to other such levers and means for concomitantly securing said lever in its withdrawn position, locking it against its said transferring motion and locking against transferring motion the wheel-carrying lever of next higher order.

8. In a totalizer, the combination of totalizer wheels, levers on which said wheels are mounted, one lever for each wheel, means for swinging the levers to move their wheels along their respective actuators to transfer the tens, a construction whereby one or more individual levers may be set at will to an inactive position such that the wheel or wheels mounted thereon cannot engage their respective actuators, and a lug on one lever and a lug on the next lever of lower order, the latter said lug when its lever is set inactive engaging the former and locking the former lever against transfer movement.

JOHN MUELLER.
